UNITED STATES PATENT OFFICE.

JOSEPH JACOBS, OF LAKE CHARLES, LOUISIANA, AND ALBERT JACOBS, OF NEW YORK, N. Y.

GARMENT-HANGER.

1,344,697.

Specification of Letters Patent. Patented June 29, 1920.

Application filed November 7, 1919. Serial No. 336,279.

To all whom it may concern:

Be it known that we, JOSEPH JACOBS and ALBERT JACOBS, citizens of the United States of America, residing at Lake Charles, parish 5 of Calcasieu, State of Louisiana, and 215 Fourth avenue, New York, county of New York, State of New York, respectively, have invented certain new and useful Improvements in Garment-Hangers, of which the 10 following is a specification.

This invention relates to garment hangers and it has for its object the provision of an improved device of this character constructed in such manner that it may be 15 manufactured at a very small cost, will hold garments in a natural and proper shape during the time that the device is in use and upon which the garment may be mounted with a minimum of trouble.

20 Further objects and advantages of the invention will be set forth in the detailed description which now follows.

In the accompanying drawing

Figure 1 is a side elevation of a garment hanger constructed in accordance with the 25 invention;

Fig. 2 is an underside plan view thereof; and

Fig. 3 is a detailed sectional view upon 30 line 3—3 of Fig. 1.

Like numerals designate corresponding parts in all of the figures of the drawing.

Referring to the drawing it will be seen that the body portion of the hanger is made 35 of two parts 5^a and 5^b united by a lap joint at 5^c and disposed at an obtuse angle with relation to each other so that when a coat is hung thereon the back of the coat is stretched in substantially the same position 40 that it occupies when upon the wearer. A hook 6 provides means for hanging the structure upon any desired support. The member 5^a is cut out at 7 to receive the end of a trousers supporting rod 8. The opposite 45 site end of this rod is pivoted by means of a pin 9 within the member 5^b in such manner as to permit a limited lateral and vertical movement of the free end of the rod 8. A wire 9^a is bent at 10, 11 and 12 and its free 50 ends are engaged with the member 5^a in

such manner as to form a detent into which the free end of the rod 8 may be snapped. A pin 13 projects downwardly from the member 5^a and has a recessed lower end 14 in which the body of the rod 8 engages. By 55 freeing the end of the rod 8 from the wire detent and swinging the same laterally a looped pair of trousers may be slipped upon said rod and the rod may then be thrust back into engagement with the detent which, 60 act binds the trousers between the pin 13 and the rod 8 and thereafter prevents the trousers from slipping off of said rod.

It is to be understood that the invention is not limited to the precise construction set 65 forth but that it includes within its purview whatever changes fairly come within either the terms or the spirit of the appended claims.

Having described our invention, what we 70 claim is

1. A garment hanger comprising a body portion made of two pieces which lie at an obtuse angle with relation to each other, a trousers supporting rod loosely pivoted at 75 one of its ends to one of said members, a detent carried by the other of said members for engaging the free end of said rod and a pin depending from the last named member and projecting into the path of movement 80 of said rod.

2. A garment hanger comprising a body portion shaped to receive a coat, said body portion being provided with an underside notch adjacent one of its ends, a wire having its ends engaged with said body portion and having its intermediate portion bent to form a recess, a trousers supporting rod loosely pivoted to said body portion at the side thereof remote from said detent and 90 having its end shaped to engage in said detent and a stop projecting downwardly from the body portion and having a recessed lower end to receive said trousers supporting rod. 95

In testimony whereof we affix our signatures.

JOSEPH JACOBS.
ALBERT JACOBS.
